BEN B. LAMPREY, OF WESTFIELD, MASSACHUSETTS, ASSIGNEE OF ONE-HALF TO
ETHEL L. LAMPREY, OF WESTFIELD, MASSACHUSETTS; ETHEL L. LAMPREY
ADMINISTRATRIX OF SAID BEN B. LAMPREY, DECEASED.

BOILER.

1,163,602.

Specification of Letters Patent. Patented Dec. 7, 1915.

Application filed January 26, 1915. Serial No. 4,470.

To all whom it may concern:

Be it known that I, BEN B. LAMPREY, a citizen of the United States of America, residing at Westfield, in the county of Hampden and State of Massachusetts, have invented a new and useful Boiler, of which the following is a specification.

My invention relates to improvements in steam or hot-water boilers for heating buildings, and resides in a certain peculiar arrangement of manifolds and connecting tubes or pipes, as hereinafter more fully set forth.

The primary object of my invention is to produce a boiler for heating purposes, which is compact, strong and durable, and so constructed that it has very little radiating surface, but instead presents or comprises the maximum amount of heating surface, hence is highly efficient and most economical. In this last particular it is to be noted that, by decreasing or cutting down the amount of radiating surface to the minimum, the loss of heat is proportionately decreased and the heat conserved for its legitimate purpose, in a boiler of this type, of converting water into steam or heating the water so that the same will circulate through a system of hot-water pipes, and my construction is designed with this particular end in view.

Another object is to provide a steam or hot-water boiler that can be readily repaired in case a break occurs in any part thereof, by replacing the broken or impaired part.

Still another object is to afford means for easily cleaning out my boiler.

Other objects and advantages will appear in the course of the following description.

I attain the objects and secure the advantages of my invention by the means illustrated in the accompanying drawings, in which—

Figure 1 is a top plan of a boiler, without the casing and its appurtenances, which embodies a practical form of my invention; Fig. 2, a front end elevation of said boiler, and, Fig. 3, a side elevation of the same, some of the pipes being broken away in this view to expose others on the opposite side, and the upper portion of the steam drum also being broken off.

Similar numerals designate similar parts throughout the several views.

Any ordinary and suitable casing, with the fire-pot, grate, and accessories that belong thereto or therewith, is, in practice, provided for the heating elements herein shown and described and which constitute the present invention, but inasmuch as such casing, with the parts and members which are more or less closely associated therewith, is not a new feature and does not form a part of said invention, the same is not shown, as hereinbefore observed. I have, however, represented the new elements as resting on a base plate 1 which is supported by a pair of side base pieces 2, but these members are also old.

Although I have illustrated and will describe in detail a preferred form of construction of my boiler, it is to be understood that various modifications and changes in the shape, size, construction, and arrangement of some or all of the parts thereof may be made without departing from the nature of the invention.

The boiler shown is provided with a steam drum 3, but this may be omitted and the boiler used as a hot-water heater.

Passing now to a detailed description of the boiler, it will be observed that the same comprises two bottom side manifolds 4 and 5, which rest on the plate 1, a series of pipes 6 which rise from said manifold 4, a side manifold 7 mounted on said pipes over said manifold 4, a series of pipes 8 which rise vertically from said manifold 5 and extend over horizontally to said manifold 7, a bottom end manifold 9 which rests on said plate, a series of pipes 10 which rise vertically from said manifold 9 and extend horizontally forward, over the horizontal parts of said pipes 8, to the front end of the boiler, and a manifold 11 at the front ends of said pipes 10. In addition to these parts and members there are other necessary elements which will presently be described.

The pipes 6 open at the bottom into the top of the manifold 4 and at the top into the bottom of the manifold 7. The pipes 8 open at one end into the top of the manifold 5 and at the opposite end into the manifold 7 through the inner side thereof. The

pipes 10 open at one end into the top of the manifold 9 and at the other end into the manifold 11 through the back side thereof.

Parallel with the manifold 9 and behind the same is a tubular connection 12, and opening into the ends thereof and into the rear ends of the manifolds 4 and 5 respectively are two pipes 13 and 14, while a pipe 15 opens into said connection at an intermediate point and into the back side of said manifold 9 at an intermediate point. Thus the manifolds 4, 5 and 9 are in communication with each other. By providing the connection 12 with removable caps or plugs 16 opposite the rear ends of the pipes 13, 14 and 15, as is done, provision is made for conveniently obtaining access to the interior of said manifolds for the purpose of cleaning them out, it only being necessary to remove said plugs and introduce the proper implement into the manifolds through said connection and pipes.

Rising from the top of the manifold 7 and opening into the same is a tubular connection 17. The steam drum 3 is mounted on the connection 17 and the latter opens into the bottom of the former. An angular tubular connection 18 opens at one end into the top of the manifold 11 and at the other end into the connection 17. Leading downward from the connection 17 is a tubular connection 19. The connection 19 opens at the top into the connection 17 and at the bottom into the manifold 4, through the outer side and just above the floor thereof.

A water-leg 20 may be provided for the protection of the front plate of the casing (not shown). The water-leg 20 communicates at the left-hand end, through a tubular connection 21, with the front end of the manifold 4, and at the opposite end, through a tubular connection 22, with the corresponding end of the manifold 11, below which manifold said water-leg is located on the plate 1.

The space for the elements of combustion, or for the container therefor, is below the horizontal portions of the pipes 8, in front of the manifold 9 and the vertical portions of the pipes 10, between the manifolds 4 and 5 and the pipes 6 and 8 or the vertical portions of the latter, and behind the water-leg 20 and the space between that and the manifold 11.

Water is introduced into the boiler preferably through or into one of the manifolds 4 or 5, and I have in this case shown an opening 23 in the outer side of the manifold 5 for that purpose—see Fig. 3. When the boiler is complete and set up a water supply pipe leads to the opening 23 and discharges therethrough.

In order to enhance the heating capacity and decrease the radiating capacity of the boiler a non-combustible sheet, as shown at

24 in Figs. 1 and 3, may be placed above or on top of the horizontal portions of the pipes 8. This sheet confines the heat to the aforesaid portions of the pipes 8, and causes it to spread out and escape in great volume around the edges of said sheet before coming into contact with the horizontal portions of the pipes 10. Thus radiation from the horizontal portions of the pipes 8 is lessened, and this without taking the heat away from the corresponding portions of the pipes 10.

It will now be seen that, when water is admitted through the opening 23 to the manifold 5, such water will enter the other bottom manifolds 9 and 4, by way of the pipe 14, the connection 12 and the pipes 15 and 13, also the water-leg 20, by way of the connection 21, and will rise in said manifolds and water-leg and in the pipes 6 and the vertical portions of the pipes 8 and 10 to the required or desired height. It will be seen, furthermore, that, when this water is heated, the steam generated therefrom will pass from the pipes 6 and 8 to the manifold 7 and from thence, by way of the connection 17, to the drum 3, and from the pipes 10 to the manifold 11 and from thence, by way of the connections 18 and 17, to said drum, while the condensation from said drum passes down through said connection 17 and the connection 19 to the manifold 4 to be regenerated into steam. The connection 22 opens into the water-leg 20 at a higher level than does the connection 21, wherefore any steam that may be generated in said water-leg rises through said connection 22 into the manifold 11.

By simply removing the drum 3 and making connection with the hot-water piping system of a building, the boiler is converted from a steam-heater into a hot-water heater and operates as such.

Whether used as one type of heater or the other, the heating capacity of the boiler is the same; that is to say, the heating elements for the water, they being the members which contain the water or the water and steam, are heated alike in either case, or have the same area exposed to the fire and present the same area of heated surface to the water or water and steam in both cases. The boiler, when used in either capacity, possesses the highest efficiency, owing to the particular construction and arrangement as hereinbefore described, which fact will be very apparent and readily appreciable to anyone skilled in the art.

The major portion of the sheet 24 is broken away in the first view so as to permit some of the pipes under said sheet to show in full.

What I claim as my invention, and desire to secure by Letters Patent, is—

1. A boiler comprising oppositely disposed bottom manifolds and a superimposed

manifold, the latter being above one of said bottom manifolds, straight pipes between the manifolds that are on the same side, angular pipes between the bottom manifold on the other side and said superimposed manifold, a bottom rear manifold, an upper front manifold, and pipes between said two last-mentioned manifolds.

2. A boiler comprising oppositely disposed bottom manifolds and a superimposed manifold, the latter being above one of said bottom manifolds, straight pipes between the manifolds that are on the same side, angular pipes between the bottom manifold on the other side and said superimposed manifold, a bottom rear manifold, an upper front manifold, pipes between said two last-mentioned manifolds, outlet connections leading from said two upper manifolds, and an outlet common to both of said connections.

3. A boiler comprising oppositely disposed bottom manifolds and a superimposed manifold, the latter being above one of said bottom manifolds, straight pipes between the manifolds that are on the same side, angular pipes between the bottom manifold on the other side and said superimposed manifold, a bottom rear manifold, an upper front manifold, pipes between said two last-mentioned manifolds, outlet connections leading from said two upper manifolds, an outlet common to both of said connections, and a condensation connection between one of said outlet connections and one of said first-mentioned bottom manifolds.

4. A boiler comprising oppositely disposed bottom manifolds and a superimposed manifold, the latter being above one of said bottom manifolds, straight pipes between the manifolds that are on the same side, angular pipes between the bottom manifold on the other side and said superimposed manifold, a bottom rear manifold, an upper front manifold, pipes between said two last-mentioned manifolds, and connections between said bottom side and rear manifolds.

5. A boiler comprising oppositely disposed bottom manifolds and a superimposed manifold, the latter being above one of said bottom manifolds, straight pipes between the manifolds that are on the same side, angular pipes between the bottom manifold on the other side and said superimposed manifold, a bottom rear manifold, an upper front manifold, pipes between said two last-mentioned manifolds, a rear-end connection provided with removable members, and pipes connecting said connection with said bottom side and rear manifolds, each of said last-mentioned pipes being in line with one of said removable members.

6. A boiler comprising oppositely disposed bottom manifolds and a superimposed manifold, the latter being above one of said

bottom manifolds, straight pipes between the manifolds that are on the same side, angular pipes between the bottom manifold on the other side and said superimposed manifold, a bottom rear manifold, an upper front 70 manifold, pipes between said two last-mentioned manifolds, connections between said bottom side and rear manifolds, outlet connections leading from said two upper manifolds, and an outlet common to both of said 75 connections.

7. A boiler comprising oppositely disposed bottom manifolds and a superimposed manifold, the latter being above one of said bottom manifolds, straight pipes between 80 the manifolds that are on the same side, angular pipes between the bottom manifold on the other side and said superimposed manifold, a bottom rear manifold, an upper front manifold, pipes between said two last-mentioned manifolds, connections between said bottom side and rear manifolds, outlet connections leading from said two upper manifolds, an outlet common to both of said outlet connections, and a condensation connection 90 between one of said outlet connections and one of said first-mentioned bottom manifolds.

8. A boiler comprising oppositely disposed manifolds and a superimposed manifold, pipes between one of said bottom manifolds and said superimposed manifold, pipes between the other of said bottom manifolds and said superimposed manifold, a bottom rear manifold, an upper front manifold, 100 pipes between said two last-mentioned manifolds, connections between said bottom manifolds, a water-leg under said upper front manifold, a connection between said water-leg and one of said first-mentioned bottom 105 manifolds, and a connection between said water-leg and said upper front manifold.

9. In a boiler, upper and under manifolds and connecting pipes forming one side, a bottom manifold and the vertical portions 110 of angular pipes, which connect said last-mentioned manifold with said upper manifold, forming the other side, a bottom manifold and the vertical portions of angular pipes, which rise from said last-mentioned manifold and then extend forward, forming the rear end, and a manifold, with which said last-mentioned pipes are connected, at the front end, the horizontal portions of 115 said pipes forming the top.

10. In a boiler, upper and under manifolds and connecting pipes forming one side, a bottom manifold and the vertical portions of angular pipes, which connect said last-mentioned manifold with said upper manifold, forming the other side, a bottom manifold and the vertical portions angular pipes, which rise from said last-mentioned manifold and then extend forward, forming the rear end, and a manifold, with which said 125

last-mentioned pipes are connected, and a water-leg, spaced from said last-mentioned manifold, forming the front end, the horizontal portions of said pipes forming the top.

11. In a boiler, upper and under manifolds and connecting pipes forming one side, a bottom manifold and the vertical portions of angular pipes, which connect said last-mentioned manifold with said upper manifold, forming the other side, a bottom manifold and the vertical portions of angular

15 pipes, which rise from said last-mentioned manifold and then extend forward, forming the rear end, a manifold, with which said last-mentioned pipes are connected, at the front end, and a non-combustible member between the horizontal portions of said pipes, said horizontal portions with said member forming the top.
